(57) **CLAIM**

The ornamental design for an electronic instrument, as shown and described.

DESCRIPTION

FIG. 1 is a top plan view of an electronic instrument showing my new design;

FIG. 2 is a bottom plan view thereof;

FIG. 3 is a side elevational view thereof;

FIG. 4 is a side elevational view thereof;

FIG. 5 is a side elevational view thereof;

FIG. 6 is a side elevational view thereof;

FIG. 7 is a top, side perspective view thereof; and,

FIG. 8 is a bottom, side perspective view thereof.

The broken lines shown in the figures represent portions of the electronic instrument that form no part of the claimed design.
